CLAIM

The ornamental design for a footwear, as shown and described.

DESCRIPTION

FIG. 1 is a top perspective view of a footwear showing the new design;

FIG. 2 is a front elevational view of the embodiment of FIG. 1;

FIG. 3 is a rear elevational view of the embodiment of FIG. 1;

FIG. 4 is a left side elevational view of the embodiment of FIG. 1;

FIG. 5 is a right side elevational view of the embodiment of FIG. 1;

FIG. 6 is top plan view of the embodiment of FIG. 1; and, FIG. 7 is a bottom plan view of the embodiment of FIG. 1. The broken lines are for illustrative purposes only and show portions of the footwear that form no part of the claimed design.

1 Claim, 7 Drawing Sheets
